UNITED STATES PATENT OFFICE.

CHARLES F. HALL, OF SKANEATELES, NEW YORK.

APPARATUS FOR REFITTING STOP-VALVES.

SPECIFICATION forming part of Letters Patent No. 513,392, dated January 23, 1894.

Application filed March 17, 1892. Serial No. 425,231. (No model.)

To all whom it may concern:

Be it known that I, CHARLES F. HALL, a citizen of the United States, and a resident of Skaneateles, in the county of Onondaga and State of New York, have invented certain new and useful Improvements in Apparatus for Refitting Stop-Valves, of which the following is a specification.

My invention relates to apparatus for refitting the bearing surfaces of valvedisks and seats of stop valves and it consists in the improved apparatus more particularly adapted for refitting the disks and seats of "straight-way" valves of which the well known "Ludlow" valve is a type, but some parts of which apparatus may also be used in refitting ordinary stop valves, all as hereinafter fully described reference being made to the accompanying drawings, in which—

Figure 1, is a side elevation of my improved apparatus with a part in section as applied to the shell of the valve for refitting the seats in a straight way valve, said shell being shown in side elevation with a part broken out. Fig. 2, is a side elevation of part of the apparatus of Fig. 1, detached. Fig. 3, is a side elevation of other parts of the said apparatus of Fig. 1, detached. Fig. 4, is a front elevation of the devices of Fig. 3, same as viewed in Fig. 1, but detached therefrom, and it shows a part of one of the devices of Fig. 1, not shown in Fig. 3, said part being sectioned. Fig. 5, is a front elevation of a modified form of one of the devices of Figs. 3 and 4. Fig. 6, is a detail of some of the parts of Figs. 1 and 2, partly in section and showing modifications that may be adopted. Fig. 7, is a top view of the centering guide of Fig. 1. Fig. 8, is a face view of the centering guide of Fig. 1, with a valve disk applied as in the use of that part of the apparatus for refitting disks. Fig. 9, is a back or top view of the same in a modified form of construction. Fig. 10, is a side view of the centering guide in a modified form of Fig. 9, and Fig. 11, is a side elevation of the centering guide and cutter, and the appliances used therewith for refitting the valve disks.

I employ a milling cutter disk *a*, for refitting the seats *b*, or disks *c*, said cutter having a flat or conical cutting face *e*, according as the said seats are flat or conical, and for coni-

cal valve disks it will be correspondingly cup shaped. To apply the cutter to the seats *b*, in the shell *f*, of a "straight way" valve, I 55 employ a head block *g*, on a spindle *h* to be introduced through the lateral branch *i*, of the case about the same as the valves are applied, with the cutter and the spindle fitted to the head block so that they may rotate 60 freely and connected by bevel gears *j*, so that the cutter may be rotated by a hand crank as *s*, or any other approved means for rotating the spindle applied to the upper end of it, the cutter being at the same time pressed 65 against the seat *b*, on which it is taking effect by any approved means having, preferably, the opposite valve seat for a fulcrum, but any other feasible point of support may be employed. The cutter may be mounted on the 70 head-block in any approved way.

In Fig. 1, I represent the cutter provided with a pivot stud *k*, entering a socket *l*, in the head-block, and in Fig. 6, I show the head-block having a pivot stud *k'*, on which the 75 cutter having a hole in the center is fitted to turn and is secured by the tap-screw *m*; the bevel wheel *j*, belonging to the cutter is secured to it by screws *n*. The spindle *h*, has a journal *o*, extending through the head-block 80 and having a check-nut *p*, screwed on below the head-block to keep the parts in connection, and to the lower extremity of the spindle, I represent a milling cutter *q*, attached such as I employ on a like spindle in my previously patented apparatus for refitting the 85 seats of globe stop valves, the said spindle being alike applicable for use in refitting both forms of valves.

For utilizing the opposite valve seat *b*, for 90 the fulcrum from which to apply the force to press the cutter against the seat being dressed, I employ a disk *t*, connected to the head-block by a stud *u*, with a wedge *v*, between said disk and head-block to be driven forward a 95 little from time to time to set up the cutter, or the disk *t'*, connected to the head-block by the screw stud *u'*, and having sockets *w*, in the edge for the application of a lever or spanner for turning it to force up the cutter 100 by the screw stud, said lever or spanner to be applied through the lateral branch *i* and the wedge may be driven by a rod inserted through the mouth of the lateral branch or it

may have a shank x , extending above the top of the said branch to be driven by a hammer, or it may be fitted with an adjusting nut y , for feeding the wedge gradually, the nut having suitable connection with any approved means of supporting it against the resistance of the wedge, as a bracket z , attached to the disk a' , or an arm as 2, of the guide hub 3, for the spindle h . In case the said hub is made with a disk instead of arms, the disk may have holes as 23 for the shank of the wedge.

The disk t , and wedge v , are suitably tapered on the sides working together for best effects, and the wedge is bifurcated to take effect at both sides of the stud u . Any other approved means of seating the appliance on one valve seat from which to force the cutter, acting on the other seat may be employed, as for instance a cross bar, and the like device.

To guide and control the upper end of the spindle the above mentioned hub 3, is employed, together with radially adjustable jaws 4, for centering it in the open mouth of the lateral branch i , said jaws having one or more screw threaded shoulders 5, to enter the internally threaded mouth of the branch and screw in tight, said jaws being applied to radial arms of the hub, or it may be a complete disk in any approved way, so as to be shifted radially to adjust them to the size of the open screw threaded mouth and to secure them in position; as a simple means of connecting them they may be set in radial grooves as 6, in the arms or disk and secured with clamping bolts 7, in radial slots 8, or they may be fitted on screw threaded arms as 9, with an adjusting nut 10, in a slot of the jaw, and with set screws 11, to make them fast, the screw threads being suitably flattened as at 12, for the bearing points of the set screws. Any other practical mode of applying and adjusting the said jaws may of course be employed. The two threaded shoulders 5, of the jaws are differentiated radially for application of the jaws to valve cases of materially different sizes. The inner faces of the jaws are adapted for gripping the valve disks C, by the edge so that the guide for the valve spindle may also be utilized for a chuck to hold the valve disks for refitting them, in which case the hub 3, is inserted in the socket of the standard 15, with or without a spindle h' , Fig. 10, and secured by a set screw 16, while the cutter a , with the bevel wheel j re-

moved, or another suitable cutter placed on the end of a spindle 17, carried in another standard 18 within a screw threaded feeding sleeve 19, and having a crank 20, for turning it, is used to refit the valve disks so held as represented in Fig. 10.

A coiled spring 21, is applied to the spindle h , between the under side of the guide hub, and the wheel j , to hold the cross-head and other parts down, and the adjustable collar 22, is applied to the spindle above the guide hub to adjust the height of the cutter relatively to the seats to be dressed. When one seat has been dressed the apparatus is taken out and reversed and applied to the other seat for dressing it. The spring may be above and the collar below the hub if desired.

I claim—

1. In a valve refitting device the combination with the guide hub and jaws applicable to the mouth of the lateral branch of the valve, and with the rotary spindle in said guide hub, of the head block journaled on the spindle, and adapted to have support at one end laterally to the spindle, and the cutter journaled in the head block and geared with the spindle substantially as described. 75

2. In a valve refitting device the combination with the guide hub and jaws applicable to the mouth of the lateral branch of the valve, and with the rotary spindle in said guide hub, of the head block journaled on the spindle, and adapted to have support at one end laterally to the spindle, adjusting devices between said head block and its support, and 80 the cutter pivoted on the other end of said head block and geared with the spindle substantially as described. 85

3. In a valve refitting device the combination with the guide hub and jaws applicable to the lateral branch of the valve, and with the rotary spindle in said guide hub, of the head block journaled on the spindle, the cutter pivoted on the head block and geared with the spindle, and the coiled spring and adjustable collar on the spindle above and below the guide hub respectively substantially as described. 95

Signed at Skaneateles, in the county of Onondaga and State of New York, this 12th 105 day of February, A. D. 1892.

CHARLES F. HALL.
